CAN OPENER

Walter W. Edlund, Burlington, Vt., assignor to
 Edlund Company, Inc., Burlington, Vt., a corporation of Vermont

Application July 9, 1951, Serial No. 235,752

15 Claims. (Cl. 30—6.4)

1

The present invention relates to can openers, and more particularly to that type of can opener of the household size for mounting on a wall.

An object of this invention is to provide a can opener which comprises a single unitary housing with the operating mechanism disposed therein, said housing being adapted to be rigidly mounted to a vertical surface to prevent wobbly movements during the can opening operation.

Another object of the invention is to furnish a can opener of the type disclosed which is stationarily mounted on a vertical surface in a compact manner, this position of mounting being the same during the can opening operation as when the opener is not in use.

Still another object of the present invention is the provision of a simplified means whereby the bead of a can being opened is constantly being urged toward a portion of the housing acting as a stop member. This means includes the use of a spiral cut feed gear which contacts the outer periphery of the bead of the can.

A further object of the invention is to furnish a permanent magnet removably mounted over the top of the can which is being opened, said magnet grasping the lid when it is completely severed from the can and holding it until the can is removed from the opener. Then the lid may be removed from the magnet by hand.

A still further object of this invention is the provision of an operating handle which rotates on an axis longitudinal with respect to the operator, said handle controlling, by a camming action, a pivotally mounted lever having a cutting tool on the lower end thereof. Resilient means is furnished to resist said camming action and to urge said tool toward the above-mentioned spiral gear so that the bead of the can to be opened will be secured between the tool and the gear.

These and other objects and advantages of the invention will become apparent from the following description of the present invention illustrated in the accompanying drawing, in which:

Figure 1 is a broken away sectional view of the present invention showing the arrangement of the operating mechanism inside the housing;

Figure 2 is a front elevation of the invention showing the compact design and the sturdy mounting means;

Figure 3 is a front elevation of the handle operated lever;

Figure 4 is a rear elevation of the magnet and its housing; and,

Figure 5 is a plan view of the lower partition which is mounted in the housing.

Figure 6 is an elevational view of the handle operating lever showing a disk cutting tool mounted thereon.

Similar reference characters in the several figures indicate similar parts.

Conventional can openers of the household type take many forms. Many of the openers are removably mounted on a bracket secured to a

2

wall and are adapted to lie close to the wall when not in use. When it is desired to remove the top of a can the opener is swung out away from the wall. A disadvantage of this type of construction is the tendency of such openers to become wobbly or loose. Also the necessity of swinging the operating bar out from the wall, effecting the opening operation and then swinging the bar back to the wall, requires more time of the operator. Further, means must be provided to maintain the operating bar sufficiently rigid during the opening operation. Therefore, the lever must be lifted before it can return to a position against the wall. Other types of openers must be lifted or tilted from an inoperative position to an operative position. Conventional can openers usually require a separate lever mounted on the operating bar for puncturing the can.

The present invention has been designed to obviate these requirements and considerably simplifies the can opening operation.

The housing illustrated generally by the numeral 10, is elongated and in the form of a channel, which includes a web or front portion 11 and flange or side portions 12 and 13. The housing is adapted to be mounted on a vertical surface by flanges 14 and 15 so that its longitudinal axis extends in a vertical direction. These flanges are integral with side portions 12 and 13, and extend in a plane normal thereto. An aperture is furnished in flanges 14 and 15 adjacent the upper end thereof to receive screw means for securing the housing to said vertical surface. It will be noted that the mounting flanges are positioned intermediate the upper and lower ends of the housing, and are of such a width as to provide sufficient bearing surface on the wall to insure rigidity. Of course, the rear edge of the side portions also bear against the wall to provide further rigidity. The complete housing already described is formed from a single piece of metal which decreases cost and simplifies the manufacturing operation.

The upper edges of side portions 12 and 13 are tapered upwardly from the front portion to the wall, these edges being illustrated by numerals 12a and 13a.

At the lower end of the side portions a pair of parallel outwardly extending members 16 and 17 are formed. Retaining grooves 18 and 19 are fashioned in these flanges for receiving the housing of a permanent magnet. Each of these flanges are undercut at the rear end thereof to provide a recess 20. Side portions 12 and 13 extend downwardly below said recesses to tapered edges 22 and 23, respectively. Aligned apertures 24 and 25 are formed in the lower ends of said side portions. A cylindrical roller 26 is mounted between the lower ends of the side portions and is maintained therebetween by means of a bolt 27 which is received by apertures 24 and 25.

To maintain the side portions parallel, par-

titions 28 and 29 are utilized. These partitions may be secured to the side portions in any convenient manner. As here shown I provide aligned slots in the side portions for receiving projections on the partitions. The ends of the projections extend slightly beyond the outer surface of the side portions and are then upset to prevent their withdrawal from the slots.

Partition 28 is angular in cross section, having a vertical leg 30 and a horizontal leg 31. Each leg portion is bored to provide apertures 30a and 31a. Partition 29 is mounted at the lower end of the housing and has an extension 32 which is adapted to rest in recesses 26. The central portion of this extension is cut out to form a recess 33 to permit the cutting tool to rest therein. The outer portions of the extension, represented by numerals 32a and 32b act as stop members to limit the upward movement of the can which is being opened. An aperture 29a is provided in partition 29 to rotatably receive the lower end of vertical shaft 34, the other end of said shaft being journaled in aperture 31a in partition 28.

A cogwheel 35 is secured to the upper end of shaft 34 for rotation therewith, said cogwheel being spaced from leg 31 of the partition by a raised annular shoulder 36 formed concentric with aperture 31a. A feed gear 37 is mounted on the lower end of said shaft, said gear being provided with an axially threaded aperture 38 and peripheral teeth 39, said aperture threadingly receiving the threaded end of shaft 34. Teeth 39 do not extend exactly parallel to the vertical axis of the rotor but instead are cut in a helical pattern. This specific design for the feed gear acts upon the bead of the can being opened in such a manner that the bead is always lifted up to the stops 32a and 32b on partition 29. Also, this design prevents the can from dropping out of cutting position.

I have provided a simplified means of rotating shaft 34. As mentioned above, most can openers have a handle operated on a transverse axis. This means that the axis of rotation must be spaced from the wall, where the opener is mounted, at least a distance equal to the length of the handle. Further, an additional distance must be provided in order to prevent the operator's hand from striking the wall. This of course means that the opener must project outwardly from the wall such a distance as to become unsightly. As heretofore mentioned, many of the openers are swung back against the wall, but again the device is still unsightly. Further, while the opener is in operative position, the axis of rotation of the handle is spaced so far from the wall that rigidity in the device is lost.

The present means for providing rotation for shaft 34 is very compact and is spaced from the wall such a short distance as to prevent wobbly operation. The axis of rotation of the handle is longitudinal with respect to the operator. An aperture 40 is formed in front piece 11 in axial alignment with aperture 36a of partition leg 39. A bushing 41 is adapted to be positioned in aperture 40 for reciprocation therein, said bushing having a concentric bore 42. Shaft 43 is adapted to be journaled in aperture 36a and bore 42. A cogwheel 44 is fixedly secured to shaft 43 for meshing engagement with cogwheel 35. Near one end of shaft 43 a turned-down portion 45 is provided to fit in aperture 39a. The end is turned down slightly more and screw threads are formed thereon. Nut 46 is utilized

to secure the shaft in position. The reciprocation of bushing 41 is accomplished by means of a pair of cam ears 48 located on the enlarged end of an operating handle 47.

A square head 48 is provided on one end of shaft 43 and ears 48 are secured thereto by rivet 49. Handle 47 has a conventional rotatable knob 50 at the outer free end thereof. One corner of the enlarged end of the handle is beveled as at 51. When knob 50 is pulled outwardly a short distance, beveled surface 51 contacts bushing 41 and forces it inwardly along shaft 43.

The reason for reciprocating bushing 41 inwardly is to permit the bead of a can to be grasped between the cutting tool 52 and the spiral feed gear 37. This is accomplished by the use of a lever 53 pivotally mounted in housing 10 by the use of bolt member 53a, said bolt being received by aligned apertures in the housing and lever. The lever itself comprises a pair of parallel vertical members 54 and 55 connected at their rear edges by cross members 56 and 57, all of said members of the lever being integral with each other. At the upper end of said vertical members, flange-like ears 54a and 55a extend inwardly from the forward edges. These ears abut the inner surface of bushing 41.

It is possible to utilize cutting tools of various shapes and constructions with my device. For instance, a disc type cutting tool such as is commonly used with can openers may be used. In the modification of my device shown in Figures 1-3, I show the use of a cutting tool which consists of a blade fixed to the lever 53. It is obvious that a disc type wheel, for instance, may be fixed to the lever 53 in place of the blade 55. In Figure 6 there is shown a disc cutting tool 52a connected to the lever 53b.

The lower end of cross-member 57 has an aperture 58 therein. Knife blade 52 is adapted to lie against the lower portion of this cross member, said blade having an aperture 59 in alignment with aperture 58. To connect the blade to the cross-member a bolt 60 is utilized, said bolt passing through aperture 59 and is threadingly received in aperture 58. The usual cutting edge is furnished at the lower end of the blade and is indicated by numeral 61.

It will be seen that whenever knob 50 is pulled outwardly away from its normal position, beveled edge 51 contacts bushing 41 and moves it axially along shaft 43. During the travel of the bushing it contacts ears 54a and 55a causing the lever to pivot about bolt 53a. In doing so blade 52 is moved outwardly away from the spiral feed gear, permitting the bead of a can to be inserted therebetween. However, it is apparent that if the top of the can is to be removed, the blade and gear must form a bite on the bead. Therefore, I utilize a coil spring 62. One end of the coil spring rests in a seat 63 formed in cross member 57 and the other end rests in the adjusting screw 64, the latter end being received by the hollowed-out interior of the screw illustrated by numeral 65. By adjusting screw 64 the compressive force, on the lower portion of lever 53 is regulated. This, of course, determines the force with which blade 52 and gear 37 grip the bead of the can.

Another feature of applicant's invention is the addition of a small permanent magnet 66 positioned in such a manner to grip the top lid whenever it is severed from the can, thus permitting the operator to remove the can without fear of having the lid sink down into the contents of the

can. This magnet is mounted in a housing 67 and is secured thereto by inturned flanges 68. The housing includes a front piece 69 having an angularly extending inscribed line 70 on the face thereof. The expression "Start can this angle" is also inscribed on the face of the front piece. At each side of the housing I furnish a flange 71 having a raised surface 72, the latter being complementary with grooves 18 and 19 in projections 16 and 17, respectively.

The operation of the can opener will now be described in detail. First, it is necessary to mount the housing on a vertical surface. This is accomplished by placing screws in the apertures in flanges 14 and 15 and securing these screws to said vertical surface. Next, knob 50 is pulled outwardly away from housing 10, thereby further displacing blade 52 from feed gear 37. The bead of the can is placed between blade 52 and feed gear 37, with the top of the can in parallelism with inscribed line 70, and knob 50 is permitted to return to its normal position. Then the handle is rotated about its axis thereby rotating feed gear 37. Since teeth 39 are arranged in a spiral pattern they tend to force the can upwardly causing the blade edge 61 to enter the can. As the rotation continues the upper edge of the bead rises until it abuts members 32^a and 32^b of partition 32. After completion of the cutting operation the severed lid is grasped by magnet 66. The can is removed from between the blade and feed gear by pulling outwardly on knob 50.

A decorative cap 13 is adapted to fit over the upper end of housing 10. This cap has a raised surface 14 which fits in complementary relation with raised surface 75 on side members 12 and 13.

From the foregoing detailed description it will be apparent that I have provided a can opener which accomplishes the objects set forth. This opener combines compactness of design and rigidity of operation with an efficient and yet simple cutting mechanism. The device is so designed that there are but few parts to be manufactured and each of these has all separate parts formed integrally by stamping or other similar process. The assembly of the parts can be simply carried out and are positioned in the housing in a logical manner.

While I have shown and described a preferred form of my invention, it will be understood that variations in details of form may be made without departure from the invention as defined in the appended claims.

I claim:

1. A can opener comprising a housing, upper and lower partitions mounted in said housing, said partitions having aligned apertures therein, a shaft journaled in said apertures, a second shaft journaled in said housing and one of said partitions, means operatively connecting said shafts, a handle mounted on said second shaft for rotation thereof, a toothed feed gear secured to the lower end of the first-mentioned shaft, a lever pivotally mounted in said housing having cutting means mounted on the lower end thereof, said cutting means being positioned adjacent said feed gear, and means urging pivotal movement of said lever and said cutting means toward said feed gear.

2. A can opener comprising a housing, a shaft journaled in said housing, a second shaft journaled in said housing, means operatively connecting said shafts, a handle mounted on said second shaft for rotation thereof and pivotal on said shaft, a toothed feed gear secured to the lower end of the first mentioned shaft, a vertically ex-

tending lever, means pivotally mounting said lever in said housing, a cutting means mounted on the lower end of said lever adjacent said feed gear, the upper end of said lever being positioned adjacent said second shaft, a bushing mounted on said second shaft adjacent the upper end of said lever and between said upper end and the handle, said bushing and the upper end of the lever being pushed away from the handle end of said second shaft by outward pivotal movement of the end of said handle thereby moving said cutting means away from said feed gear, and means urging said cutting means toward said feed gear when the end of said handle returns to its normal position.

3. A can opener comprising a housing, a vertical shaft journaled in said housing, the lower end of said shaft having a toothed feed gear thereon, a second shaft journaled in said housing above the first mentioned shaft, means operatively connecting said shafts, a handle pivotally mounted on one end of said second shaft for rotation of said shaft and for pivotal movement of the end thereof outwardly away from said housing, a vertically extending lever pivotally mounted in said housing, a cutting tool secured to the lower end of said lever in a position adjacent said feed gear, the upper end of said lever being positioned so as to be moved by said handle upon pivotal movement thereof so that pivotal movement of the end of said handle forces the upper end of the lever away from the handle end of said second shaft thereby moving said cutting tool relative to said feed gear, and means resiliently resisting said relative movement.

4. A can opener comprising a housing adapted to be mounted on a vertical surface, said housing including face and side portions, said side portions being parallel to each other and perpendicular to said face portion, said face and side portions being elongated and extending in a vertical direction, each of said side portions having rear edges adapted to abut said vertical surface, a flange integral with each of said rear edges and extending outwardly therefrom in a plane parallel to said face portion and adapted to be rigidly secured to said vertical surface, upper and lower partitions mounted in said housing, a shaft journaled in said partitions, a second shaft journaled in said face portion and one of said partitions, means operatively connecting said shafts, a handle mounted on the end of said second shaft adjacent said face portion, a toothed feed gear secured to the lower end of the first mentioned shaft, a cutting tool mounted in said housing with the lower portion thereof adjacent said feed gear, and means urging said tool toward said feed gear.

5. A can opener comprising an elongated channel-shaped housing including face and side portions, each of said side portions having a free edge opposite to the edge connected to said face portion, outwardly extending flanges mounted on each of said free edges, said flanges and free edges being adapted to lie against a vertical surface with the flanges rigidly secured thereto, upper and lower partitions in said housing for connecting said side portions, said partitions having aligned apertures therein, a shaft journaled in said apertures, a second shaft journaled in said housing and one of said partitions, means operatively connecting said shafts, a handle mounted on said second shaft for rotation thereof, a toothed feed gear secured to the lower end of the first mentioned shaft, and a cutting tool

mounted in said housing with the lower portion thereof adjacent said feed gear.

6. A can opener comprising a housing, upper and lower partitions mounted in said housing, said partitions having aligned apertures therein, a shaft journaled in said apertures, a second shaft journaled in said housing and one of said partitions, means operatively connecting said shafts, a handle mounted on said second shaft for rotation thereof, a toothed feed gear secured to the lower end of the first mentioned shaft, a cutting tool mounted in said housing with the lower portion thereof adjacent said feed gear, and a magnet removably mounted in said housing adjacent said tool.

7. A can opener comprising a housing, upper and lower partitions mounted in said housing, said partitions having aligned apertures therein, a shaft journaled in said apertures, a second shaft journaled in said housing and one of said partitions, means operatively connecting said shafts, a handle mounted on said second shaft for rotation thereof, a toothed feed gear secured to the lower end of the first mentioned shaft, a cutting tool mounted in said housing with the lower portion thereof adjacent said feed gear, a pair of spaced projections extending outwardly from said housing forward of said cutting tool, said projections having grooves formed therein, and a permanent magnet, a housing, said magnet being supported in the last named housing, flanges attached to said last named housing, said flanges having raised surfaces therein adapted to be slidably received by the grooves of said projections.

8. A can opener comprising a housing, a shaft journaled in said housing, a second shaft journaled in said housing, means operatively connecting said shafts, a handle mounted on said second shaft for rotation thereof, a toothed feed gear secured to the lower end of the first-mentioned shaft, a cutting tool movably mounted in said housing with the cutting portion thereof adjacent said feed gear, and means urging said cutting portion toward said feed gear.

9. A can opener comprising a housing adapted to be mounted on a vertical surface, vertically spaced partitions in said housing, having aligned apertures therein, a shaft journaled in said apertures, a toothed feed gear secured to the lower end of the shaft, a second shaft journaled in said housing and one of said partitions, means operatively connecting said shafts, a handle connected to said second shaft for rotating said shaft, a cutting tool movably mounted in said housing with the lower portion thereof adjacent said feed gear, said handle being movably connected to said second shaft, means actuated by movement of said handle with respect to said second shaft for moving said tool away from said feed gear, and means resiliently resisting the movement of said tool away from said feed gear.

10. A can opener comprising an elongated housing adapted to be mounted on a vertical surface, a shaft journaled in said housing, a toothed feed gear secured to the lower end of said shaft, a second shaft journaled in said housing, means operatively connecting said shafts, a handle connected to one end of said second shaft for rotation in a plane parallel to said vertical surface, a vertically extending lever pivotally mounted in said housing, a cutting tool secured to the lower end of said lever in a position adjacent said feed gear, means urging said tool toward said feed gear, said handle being pivotally mounted

5 on said second shaft and connecting means extending between said handle and said lever for causing pivotal movement of said lever upon pivotal movement of said handle on said second shaft.

11. A can opener comprising a housing, upper and lower partitions mounted in said housing, said partitions having aligned apertures therein, a shaft journaled in said apertures, a feed gear having spirally formed teeth on the periphery thereof mounted on the lower end of said shaft, a cutting tool pivotally mounted in said housing with the lower portion thereof adjacent said feed gear, means urging pivotal movement of said tool towards said feed gear, and means for rotating said shaft.

12. A can opener comprising a housing, said housing having securing means adapted to be placed adjacent a vertical surface, a shaft journaled in said housing, a spiral toothed feed gear positioned at the lower end of said shaft, a second shaft journaled in said housing for rotation in a horizontal plane, a handle mounted on one end of said second shaft for rotation of said second shaft, a vertically extending lever pivotally mounted in said housing, a cutting tool secured to the lower end of said lever in a position adjacent said feed gear, and means urging said tool toward said feed gear.

13. A can opener comprising a housing including vertically extending face and side portions, a vertical shaft journaled in said housing, the lower end of said shaft having a toothed feed gear thereon, a second shaft journaled in said housing, means operatively connecting said shafts, a handle pivotally mounted on said second shaft for rotation thereof, a vertically extending lever pivotally mounted in said housing, a cutting tool secured to the lower end of said lever in a position adjacent said feed gear, connecting means extending between said handle and said lever, said lever being pivoted by pivoting said handle outwardly of said housing so as to move said tool away from said feed gear through action of said connecting means, and means urging said tool toward said feed gear.

14. A can opener comprising a housing, a shaft journaled in said housing, a handle supported on said housing and operatively connected to said shaft for rotating said shaft, a toothed feed gear secured to the lower end of the shaft, a cutting tool movably mounted in said housing and having a cutting portion adjacent the feed gear, and means urging said cutting portion toward said feed gear.

15. A can opener comprising a housing, a shaft journaled in said housing, a handle mounted on said housing and operatively connected to said shaft for rotation thereof, a toothed feed gear secured to the lower end of said shaft, a cutting tool movably mounted in said housing and having a cutting portion adjacent said feed gear, means urging said cutting portion toward said feed gear, said handle being pivotally mounted, means for connecting said handle with said cutting tool upon pivotal movement of said handle so as to cause movement of said cutting tool away from said feed gear.
